UNITED STATES PATENT OFFICE.

RAY E. DUNHAM, OF BEREAL, OHIO, ASSIGNOR TO THE DUNHAM COMPANY, OF BEREAL, OHIO, A CORPORATION OF OHIO.

DOUBLE-GANG SOIL PACKER AND MULSHER.

1,250,570.

Specification of Letters Patent. Patented Dec. 18, 1917.

Application filed June 17, 1915. Serial No. 34,714.

To all whom it may concern:

Be it known that I, RAY E. DUNHAM, a citizen of the United States, resident of Berea, county of Cuyahoga, and State of Ohio, have invented a new and useful Improvement in Double-Gang Soil Packers and Mulshers, of which the following is a specification, the principle of the invention being herein explained and the best mode in 10 which I have contemplated applying that principle, so as to distinguish it from other inventions.

My invention relates to cultivating machines, and particularly that class of such 15 machines which is known as packers and mulshers, its object being to provide a machine of the above-named character which will be economical of manufacture and efficient in its use.

20 A specific object is to provide a structure whereby by a simple re-arrangement of parts, different operations may be performed and hence different results obtained, as may be required.

25 The said invention consists of means hereinafter fully described and particularly set forth in the claims.

The annexed drawings and the following 30 description set forth in detail certain means embodying my invention, the disclosed means, however, constituting but one of various mechanical forms in which the principle of the invention may be applied.

In said annexed drawings:

35 Figure 1 represents a plan, with parts broken away, of a device embodying my invention, showing a section of soil in connection therewith and illustrating the surface and character imparted to the soil after 40 having been operated upon by the device.

Fig. 2 represents a plan, with parts broken away, showing the parts re-arranged to produce a different result, together with a plan of a portion of soil which has just been operated upon by the machine so re-arranged.

45 Fig. 3 represents a fragmentary plan of the machine.

Fig. 4 represents a side elevation of one of the sprocket-wheels.

50 Fig. 5 represents a fragmentary axial section of one of the gangs of wheels.

Fig. 6 represents a side elevation of the complete device embodying my invention.

55 The general form of the illustrated device embodying my invention, is old and in-

cludes two lateral or side-frames, each provided with a front bearing and a rear bearing, cross braces connecting these side-frames, two transverse axles mounted in said side-frames, and a suitable tongue secured to the cross braces, together with pulverizing or mulshing disks mounted upon the axles.

Instead, however, of mounting two gangs of rollers, all of which rollers have peripheries of V-shaped cross-section, I provide one gang of rollers, each member of which has a periphery of V-shaped cross-section, and the other gang with alternately occurring sprocket-wheels and rollers having peripheries of V-shaped cross-section, as shown in the drawings. These sprocket-wheels are loose upon their shaft and the construction is preferably that shown in pending application of Ray E. Dunham and George E. Karl, Serial No. 850,005, filed July 9, 1914. Each sprocket wheel consists of a loosely turning wheel, the perimeter of said wheel being provided with teeth or spikes, as shown in Fig. 5. There are as 70 many of these sprocket wheels as there are of rollers 2, and as many of the latter as there are rollers 1, so that in the rear gang there are substantially twice as many soil disturbing units as in the first or forward 75 gang, the axial dimension of one of the rollers 1 being equal to the added axial dimensions of a roller 2 and 3.

From the nature of the loose mounting of the sprocket wheels it follows that each 80 end of the rear gang should terminate in a roller 2, in order to keep the rear gang stiff, hence it follows that the numerical relation of the two gangs may not necessarily be exactly 2 to 1; in Figs. 1 and 2 they stand 85 to 31.

In Fig. 1, I have shown the front gang provided with rollers 1, all of which have their peripheries of V-shaped cross-section and the rear gang provided with alternately 100 occurring rollers 2 and sprocket-wheels 3, the rollers 2 having a periphery similar to that of rollers 1. The combined width of a roller 2 and a sprocket-wheel 3 is made equal to the width of one of the rollers 1, and the rollers 2 and 3 are so placed upon their common axis that the sprocket-wheels 3 will be substantially in alinement with the rollers 1, as clearly shown in Fig. 1.

The front gang of wheels therefore con- 110

- sists of what are known as packer wheels and which tend to pack the soil, as well as crush all of the large lumps and to form parallel and well-defined ridges. These 5 ridges are crushed down by the rear packer wheels which hit their centers and the adjacent loose sprocket-wheels stir the surface, the ultimate compensatory effect of the latter operation being to form a mulch 10 which prevents the evaporation of moisture. The above-described operation produces a comparatively smooth surface in which the ridges are comparatively ill-defined. In some locations, however, and particu- 15 larly such as are subject to the operation of high winds, it is desirable to produce deeper ridges or corrugations that would be produced by the arrangement of parts previously described. 20 Where these deeper corrugations or ridges are desired, the location of the front and rear gangs is reversed, the alternately occurring packer and sprocket-wheels being placed in front, as shown in Fig. 2, and the 25 gang consisting entirely of packer wheels being placed in the rear. The gang consisting completely of packer wheels being now in the rear, the resultant surface will be formed into well-defined and deep ridges 30 and corrugations. These ridges are preferably formed at right angles to the direction in which the prevailing winds blow. In this last event, however, the soil is well broken up first by the front gang of wheels 35 before these deep ridges are formed. Having fully described my invention, what I claim and desire to secure by Letters Patent is:—
1. In a soil packer and mulsher, the combination of a suitable frame; a gang of wheels mounted upon said frame each of which wheels has a periphery V-shaped in cross-section; and a gang of wheels also mounted upon said frame consisting of 40 wheels having a periphery V-shaped in cross-section and sprocket wheels, such latter wheels being alternately placed upon a common axis there being in the second gang substantially as many of each kind of wheels 45 as there are V-shaped wheels in the first gang.
  2. In a soil packer and mulsher, the combination of a suitable frame; a gang of wheels mounted upon said frame each of which wheels has a periphery V-shaped in cross-section; and a gang of wheels also mounted upon said frame consisting of 55 wheels having a periphery V-shaped in cross-section and sprocket wheels, such latter wheels being alternately placed upon a common axis, the said sprocket wheels be- 60
- ing alined with the wheels of the other gang respectively, there being in the second gang substantially as many of each kind of wheels as there are V-shaped wheels in the first gang.
3. In a soil packer and mulsher, the combination of a suitable frame; a gang of wheels mounted upon said frame, each of which wheels has a periphery V-shaped in cross-section; and a gang of wheels mounted in the rear of said first-named gang on said frame consisting of wheels having a periphery V-shaped in cross-section and sprocket-wheels, such latter wheels being alternately placed upon a common axis, there being in the second gang substantially as many of each kind of wheels as there are V-shaped wheels in the first gang. 75
  4. In a soil packer and mulsher, the combination of a suitable frame; a gang of wheels mounted upon said frame, each of which wheels has a periphery V-shaped in cross-section; and a gang of wheels mounted in the rear of said first-named gang on said frame consisting of wheels having a periphery V-shaped in cross-section, and sprocket-wheels, such latter wheels being alternately placed upon a common axis, the said sprocket-wheels being alined with the wheels 80 of the other gang and the V-shaped wheels of the second gang being arranged to follow the depressions between the wheels of the forward gang, whereby the second gang is made to reshape the ridges left by the first 85 gang and the sprocket wheels disturb and mulsh the ridges made by the V-shaped wheels of the second gang. 90
  5. In a soil packer and mulsher, in combination, a suitable frame, a gang of soil disturbing elements mounted upon said frame, and a second gang of soil disturbing elements substantially twice the number of the elements of the first gang, half of them being in character like the elements of the 100 first gang, and approximately half being of a structure adapted to produce a soil disturbing effect of a character compensatory for the effect produced by the members of the first gang mounted upon the same 105 frame. 110
  6. In a soil packer and mulsher, in combination, a frame, a gang of packer wheels mounted upon said frame, and a gang of alternate packer wheels and mulshers 115 mounted upon said frame, in line with the first named gang, the number of packer wheels in the two gangs being approximately the same. 120

Signed by me, this 15th day of June, 1915.

RAY E. DUNHAM.
